SUPERHEATER ASSEMBLY

Charles S. Turner, Detroit, Mich.

Application February 1, 1932, Serial No. 590,108

Renewed October 6, 1934

7 Claims. (Cl. 122—473)

This invention relates to superheater installations, and has for its object a relatively cheaply installed, and yet efficient, construction, by means of which a bank or group of superheater tubes 5 may be installed in positions of maximum radiant heat exposure, with their terminal fittings or connections adequately protected against a degree of heat, which, under frequently encountered operating conditions, would cause the rapid 10 deterioration thereof, while the superheater tubes themselves will, because of their special and preferred construction, last an indefinitely longer time without noticeable impairment.

These terminal fittings, which are usually of 15 cast, one-piece construction, are of course designed to handle, receptively at one end of their respective superheated tubes and distributively at the other end thereof, not only the supply of steam whose superheating is desired, but as well 20 the cooling fluid column whose surrounding walls are generally integrated with the wall of the superheater tube proper, and, if the superheater units are, as well, equipped with integrated cleaning or blower jet pipes, the cooling influence of 25 the fluids passing through one or both of these is sufficient to protectively influence the temperature of the superheater tube walls against unduly rapid heat impairment.

This, for the reasons above stated, not being 30 the case as to the generally cast terminal fittings of the several superheater tubes, particularly if either the cooling column or the soot-blower elements are not active, special protective constructions for these terminal fittings become 35 necessary. My preferred construction for effecting this illustrated in the accompanying drawings, wherein

Figure 1 is an elevational view, partly in section, of a tubular boiler installation equipped as 40 well with my superheater protective elements.

Figure 2 is a plan view from above, showing a 45 plurality of superheater tubes in their extent across the flue space in a furnace chamber, and emphasizing the positioning of the terminal fittings of the superheater tubes behind both the baffles and whatever number of boiler tubes it may be desired to position them.

Figure 3 is an elevational view, partly in section, showing the end fittings of a superheater tube 50 protected at one end, as in Figure 1 behind a baffle and plurality of boiler tubes, and at the other end by a wall of the furnace, through which the other end of the superheater tube extends.

Figure 4 is a sectional view illustration of a 55 preferred form of construction of companion

terminal fittings for the superheater tubes, whose protection against undue and destructive thermal conditions is desired.

Figure 5 is a longitudinal sectional view of the preferred form of terminal fitting shown cross-sectionally in Figure 4, along the line 5—5 thereof.

A represents the walls of the furnace, over whose central heat flue space B are obliquely positioned boiler tube elements C. For purposes of guidance of the gases of combustion through successive tube banks, the boiler drums as G, baffles D, which generally are immediately behind one or more of the boiler tubes as C', are positioned on either side, as shown, forming in effect a more or less constricted throat about the flue space B. 15 For superheating purposes, a plurality of superheater tubes, as E and F, are positioned angularly, though much more nearly in a horizontal position than the boiler tubes C, across the flue space B, of course much nearer the heat source 20 than the boiler tubes C, and directly in the path of the upwardly proceeding heat units. Each of this series of superheater tubes E or F, cooperatively with its corresponding supply tube as E' and F', of course are components of a U-shaped circulatory system, and the advantage of having each superheater tube lying at an angle to the horizon as shown lies in the fact that each leg 25 of the circulatory system as thus constituted does its share in contributing toward effective circulation, each superheater tube constituting the hot leg of the U-shaped structure, while its connected feeder or supply tube constitutes the cold leg; without such an arrangement, that is to say, if the superheater tubes were positioned horizontally 30 across the flue space B, the action of some such element as a pump would be necessary to keep up 35 an adequate degree of circulation, as well as to determine the direction of circulation.

This alteration of the superheater tubes of 40 the series E and F is brought out with special clearness in plan Figure 2, wherein it will also be noted that in the showings of the terminal fittings L and N the upper or right-hand ends of 45 the several superheater elements E have their steam supply tubes E' shown in full lines and the superheater elements of the series F similarly have their steam supply tubes F' shown in full lines, the position, on the lower side of the fitting of either series of its corresponding steam discharge pipe being indicated by dotted circles at E² and F² respectively; these latter elements are of course shown elevationally in full lines in 50 Figure 1.

As stated, and as brought out particularly in 55

cross-sectional Figure 4, these superheater tube units have, in addition to the space J through which the superheated steam passes, an integrated cooling column, as K, which of course extends lengthwise of the superheater tube structure as a whole. At either end of each superheater tube proper is positioned a terminal fitting L (or N) into appropriate chambers through which, as J' and K' respectively, the superheated steam and the cooling fluid pass, at the receiving end of the superheater tube being spacedly united in relatively close assemblage by the receiving fitting, as L, while the fitting N, at the other end of the superheater tube, effects the distribution of the fluid elements respectively handled by the several guiding columns to their respective piping connections appurtenant to the furnace as a whole. Cooling water connections, generally with a common supply pipe for all of the superheater units, are shown at M.

The separate chambers J' and K' of each terminal fitting, when all are functioning, may interchange heat units to a degree sufficient to protect the component walls thereof against undue heat impairment, even when exposed to direct radiant heat action to the same degree as the superheater tubes E or F themselves. If, however, one or both of these auxiliary, heat-modifying appurtenances are not functioning, as is frequently the case, these terminal fittings, if exposed to the same degree of heat as the intermediately located superheater tubes themselves, quickly deteriorate, due to such heat exposure. I have found, however, that as contrasted with the heat to which the superheater tubes themselves are exposed, the space behind, or inside the baffles D, and also inside of, and consequently protected by, the outer row of ordinary boiler tubes, as C', is of such markedly lower temperature, even with the furnace working at capacity, that with the terminal fittings, as L and N, positioned thus, they in most cases attain only a temperature which at the worst is much more slowly destructive of the fittings than would be the case if they were, like the superheater tubes, exposed to direct radiant heat. In most cases the positioning of the terminal fittings behind the baffles and behind the first or outer row of ordinary boiler tubes, as C', is generally sufficient for the adequate protection of the terminal fittings L and N, but in case unusually high heat conditions are to be dealt with, a still further degree of protection can be secured by positioning the fittings L and N behind the second row of ordinary boiler tubes, as C², or even further back as for example, behind the still more remote tube rows as C³ and C⁴. In any event, and according to the particular circumstances of each case, a marked heat differential between the thermal conditions to which the superheater tubes, as E and F, are intentionally exposed, and those to which the terminal fittings L and N, often unprotected by cooling columns, are subjected, is effectively secured.

The modified form of construction illustrated elevationally in Figure 3 differs from that shown in Figure 1 only in that a single bank of obliquely disposed boiler tubes, as Q, is employed, each connected with drums G⁴ as before, the other or opposite side of the heat flue space R being flanked by the furnace wall W. A single baffle, as S, is here shown positioned behind a plurality of the boiler tube rows, and between the units of these rows and protectedly through the baffle S extend the superheater tubes T with their terminal fittings V and X in the same oblique position as the

superheater tubes of the series E or F in Figure 1. Though of course there may be as many superheater tubes T as may be desired, or the depth of the furnace chamber may permit, they are not alternated, as in the instance of the first described construction because of their being but one bank of inclined boiler tubes; and all of the superheater tubes T extend in the same oblique direction. The lower end of each superheater tube T of this series now being described extends through the vertical furnace wall W, so that this latter protects the lower terminal fitting, as V, against undue heating just as the baffle S, and the several rows of boiler tubes Q protects the upper terminal fitting X. The steam supply and outlet connections of the terminal fittings are the same as already described in connection with the explanation of Figure 1.

What I claim is:

1. In a furnace having baffle walls, in combination with a plurality of spacedly disposed banks of boiler tubes flanking an intermediate space between said baffle walls through which rising heat units and gases of combustion travel, a fluid-cooled superheater element extending across said space and inclined from the horizontal, having separate steam and water passages therein and metallic heat bridging portions connecting and integral with the walls of each, inlet and outlet terminals connecting said passages with the steam and water spaces respectively of the boiler, the water inlet terminal thereof being positioned below the water outlet terminal, whereby a convection current is induced in the water channel of the superheater element, and both the inlets and outlets being located outside said intermediate space and baffle walls.

2. In combination with a furnace having baffle walls and an intermediate flue gas passage, a plurality of groups of boiler tubes located in flanking position within and on either side of said passage, water-cooled superheated tube assemblies extending laterally across said passage between opposite units of each tube group and inclined from the horizontal, separate steam and water channels in each of such tube assemblies and having walls, metallic heat bridges integral with and connecting the walls, a water inlet in the lower end of each assembly, and a water outlet at its higher end, said inlets and outlets being arranged outside said baffle walls and intermediate passage.

3. In combination with a furnace incorporating steam generating means and having a combustion chamber, superheating means comprising steam and water conduit portions arranged closely appurtenant one another and extending across the combustion chamber at an angle to the horizontal, integral heat bridging portions connecting said steam and water conduit portions, and inlet and outlet connections for the water conduit portions arranged outside the combustion chamber.

4. In a steam boiler, in combination with a furnace having a passage through which heated gases of combustion pass immediately after burning, and walls defining said passage, steam superheating means comprising separate steam and water conduit portions arranged adjacent one another and extending across said passage at an angle to the horizontal, integral heat bridging portions connecting said steam and water conduit portions, said conduits being extended through said walls, and inlet and outlet portions connected to the water conduit portions outside the walls.

5. In combination with a steam boiler having walls defining a passage through which heated gases of combustion pass, regulatable steam superheating means comprising separate metallic steam and water conduits extending across said passage at an angle relatively to the horizontal and in close proximity, and integral metallic heat bridging portions connecting said steam and water conduits.
10. 6. In combination with a steam boiler having walls defining a passage through which heated gases of combustion pass, regulatable steam superheating means comprising separate metallic steam and water conduits extending across said passage at an angle relatively to the horizon and in close proximity, and metallic heat bridging means extending substantially the length of the
- 5 effective portions of said conduits and integral with both the steam and water conduit portions.
7. In combination with a steam boiler having walls defining a passage through which heated gases of combustion pass, regulatable steam superheating means comprising separate metallic steam and water conduits extending across said passage at an angle relatively to the horizon and in close proximity to each other, metallic heat bridging portions extending substantially the entire effective length of said conduits and integral with both the steam and water conduit portions, said conduit portions being projected through the walls, and inlet and outlet portions connected to said conduit portions outside the walls.
